FOREIGN PATENT DOCUMENTS

CA 2965758 A1 5/2016

Primary Examiner — Ricky Pham*(74) Attorney, Agent, or Firm* — Norton Rose Fulbright Canada LLP**CLAIM**

We claim the ornamental design for an aircraft credenza, as shown and described.

DESCRIPTION

FIG. 1 is front tridimensional view of the aircraft credenza showing our new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken lines shown in the drawings are for illustrative purposes only and form no part of the claimed design.

1 Claim, 3 Drawing Sheets---
